UNITED STATES PATENT OFFICE.

FRANK H. STETSON, OF LAWRENCE, MASSACHUSETTS, ASSIGNOR TO U. S. BOBBIN & SHUTTLE CO., OF PROVIDENCE, RHODE ISLAND, A CORPORATION OF NEW JERSEY.

LOOM-SHUTTLE.

970,763.

Specification of Letters Patent. Patented Sept. 20, 1910.

Application filed June 19, 1908. Serial No. 439,358.

To all whom it may concern:

Be it known that I, FRANK H. STETSON, a citizen of the United States, residing at Lawrence, in the county of Essex and State 5 of Massachusetts, have invented a new and useful Improvement in Loom-Shuttles, of which the following is a specification.

This invention has reference to an improvement in loom shuttles and more particularly to an improvement in hand threading loom shuttles.

The object of the invention is to provide a loom shuttle with a hand threading device of simple and durable construction adapted 15 to facilitate the threading of the shuttle by hand without suction.

The invention consists in the peculiar and novel construction of the delivery end of a loom shuttle and mechanism for guiding the 20 thread to the delivery eye, as will be more fully set forth hereinafter.

Figure 1 is a top plan view of the thread delivery end of the improved loom shuttle. Fig. 2 is a side view of Fig. 1. Fig. 3 is a 25 longitudinal sectional view of Fig. 2. Fig. 4 is a cross sectional view of Fig. 2. Fig. 5 is a side view of the guide tube. Fig. 6 is an end view of the guide tube, and Fig. 7 is a bottom view of the guide tube.

Similar letters of reference indicate corresponding parts in all the figures.

In the drawings, *a* indicates the thread delivery end of the loom shuttle, *b* the bobbin, *c* the bobbin cavity, *d* a circular hole 35 connecting the bobbin cavity *c* with the recess *e*, *f* a depression formed in the top of the loom shuttle, *g* a slit connecting the depression *f* with the hole *d*, *h* a slit formed in the side of the shuttle and extending 40 down to the guide eye *i* and forming an opening to the recess *e*, *k* a circular hole extending horizontally across the end of the shuttle and in which is located the guide tube.

The plate 8 is formed with the circular 45 end 9; the bent wire finger 10 is formed with the straight portion 11; the guide tube 12 is formed with the spiral slot 13 open at

the outer end and has the cut-away portion 14.

In operative position the plate 8 is secured in the depression *f* and upon the shoulder *l* of the shuttle by the screw 15, so that there will be a slight opening or slot in between the wall of the depression *f* and the edge of the plate 8. The wire finger 10 is secured near the circular edge 50 of the plate 8 and extends backward until over the slot 13 in the guide tube 12, then down through the slot 13 and the hole 16 55 in the guide tube 12 and into the hole *n* in the shuttle, thus locking the guide tube 12 in the hole *k* formed in the shuttle.

In threading up the shuttle the yarn passes from the bobbin to the slot *m* and 60 around the circular end 9 of the plate 8, then down through the slit *g* into the circular hole *d* and into the recess *e*, and then 65 down through the slit *h*, and being guided by the bent portion of the wire finger 10 70 passes into the spiral slot 13 of the guide tube outward to the guide eye *i*.

Having thus described my invention, I 75 claim as new and desire to secure by Letters Patent;—

1. A shuttle threading device comprising a tube secured to and extending transversely to the shuttle, and having a portion of its length formed with a helical slot, and a thread guiding post penetrating said tube 80 and projecting laterally therefrom at the inner end of said slot.

2. A shuttle threading device comprising an eye-piece having a longitudinal thread passage, and a helical thread passage 85 surrounding and communicating with the longitudinal passage, and a thread guiding post projecting laterally from the eye-piece at the inner end of the helical passage.

In testimony whereof I have signed my 90 name to this specification in the presence of two subscribing witnesses.

FRANK H. STETSON.
